UNITED STATES PATENT OFFICE

HARRY E. McCANDLESS, OF ROCHESTER, NEW YORK, ASSIGNOR TO KENNEDY-MCCANDLESS CORPORATION, OF ROCHESTER, NEW YORK, A CORPORATION OF NEW YORK

FOLDING CRIB

Application filed August 27, 1929. Serial No. 388,772.

This invention relates to improvements in folding cribs, and particularly that class of folding cribs employed for the use of young children.

5 The object of the invention is to provide a crib of this kind which is simple in construction, economical to make, and which can be readily folded into a small compact space.

Another object of the invention is to provide a crib of this kind having a top or cover which is adapted to be supported on the side members between the end members and movable from a position on the crib to an inoperative suspended position in contact with 15 one of its sides when the crib is folded, and which completely closes the gap between the top and sides of the crib when in normal position.

To these and other ends, the invention consists in the construction and arrangement of parts that will appear from the following description when read in conjunction with the accompanying drawings, the novel features being pointed out in the claims following 25 the specification.

In the drawings:

Figure 1 is a perspective view of a folding crib constructed according to one embodiment of the invention;

30 Figure 2 is an enlarged fragmentary view showing the construction of the end of the top and one of the sides in open position, the suspended or folded position of the top being shown in dotted lines;

Figure 3 is an end elevation of the same;

Figure 4 is a plan view of the crib partly folded;

Figure 5 is an enlarged fragmentary view in side elevation showing how the top is 40 mounted, and

Figure 6 is a section taken on line 6-6 of Figure 5.

Similar reference numerals refer to the same parts in all the figures of the drawings.

45 The embodiment of the invention illustrated comprises side members generally referred to by the reference numerals 1 and 2, each having a post 3 at each of its ends. Arranged between the posts of each side and secured thereto are side panels, one of which is

indicated at 4, having inwardly projecting ledges 6 and 7 along their bottom edges on which springs and mattress may be supported. If desired, the panel 4 may be constructed in two parts, the upper part 8 being hinged to the lower part so that it may swing outwardly and downwardly thereon to the position shown in Figure 2. Latches or other suitable means may be employed for locking or securing the movable part 8 in normal closed position.

55 The side 1 has inwardly projecting vertical flanges 9 secured to its end posts 3 to which the end members 10 and 11 of the crib are hinged to swing inwardly when the crib is folded, as shown in Figure 4. When in normal position, the end members extend across the end of the crib to meet vertical flanges 12 mounted on the posts of the opposite side of the crib, to which they may be releasably secured by any suitable means, as by latches 11'. It will be noted that the end members cooperate with the sides to form a substantially rectangular frame. Rods or bars 13 also connect the pivoted end members with the flanges 12. Two of these bars or rods are employed with each of the ends, one adjacent or at the top and the other at or adjacent the bottom. Each of the rods 13 is pivoted at one end to the end member at a point at or adjacent its middle and at its other end to the side member 6 or the flange 12 thereon, so that when the end members are swung inwardly on their hinges, as shown in 60 Figure 4, they operate to move the sides of the crib toward each other, and when the ends are moved into contact with the side 1, the side 2 is moved to a point closely adjacent or in contact with the outer surfaces of the ends, which then occupy a position between 65 the side members.

70

With cribs of this kind, it is desirable that a top or cover be provided which can be moved into the plane of the sides when the crib is folded. To this end, a top 15 is provided which normally occupies a horizontal position resting on the top edges of the sides of the crib, and projecting laterally over the sides. On the under side of the top and adjacent its longitudinal edges are provided the 75

beads 16 and 17. The beads 16 and 17 project below the plane of the under surface of the top and engage the outer faces of the sides of the crib to retain the cover in position thereon and tightly close the gap between the top and side members to shut out drafts, insects, etc. The engagement of the bead 16 with the hinged side member 8 also serves to maintain or secure said member in normal position, shown in Figure 1. By raising the cover, the bead is moved out of the path of the hinged side member, permitting free movement thereof.

Simple and convenient means are provided for slidably securing the top to the crib and supporting it in suspended position in contact with one of its sides when the crib is folded. Said means comprises projections in the form of a pair of bolts or pins 20 mounted on the posts 3 of the rear side 2 of the crib. The pins 20 are resiliently engaged by brackets or clips 21 which are secured to the posts by any suitable means, as by screws, as shown, so that the pins may be moved axially, if desired, to detach the top. The pins project inwardly from the posts in the path of the top and engage grooves 22 provided in its ends. The grooves 22 are closed at one end and open at the other end. Secured to the top by screws or other suitable means are the keepers 23, which project over the open ends of the grooves and engage the pins 20 when the top is in its normal position on the crib. It will be readily understood that by raising the top to disengage its bead 16 from the side of the crib, it may be readily moved across the top of the crib, during which movement it slides on the pins 20 which engage the grooves at its opposite ends. It also swings on the pins 20 and when the pins engage the closed inner ends of the grooves, the top may assume a vertical position in contact with the side of the crib suspended on the pins. It will also be noted that the keepers 23 are provided with slots or openings 24 which are engaged by the pins when the top is in its normal position on the crib and the pins move out of the open ends of the grooves. The openings 24 afford access to the pins for retracting them from the keepers when it is desired to detach the top. The pins are held in their adjusted position by the resiliency of the brackets in which they are mounted. It will be noted that the top is of a length substantially equal to the distance between the end posts of the sides between which it moves to and from operative position. By this construction, the top is arranged between the end members and the posts, permitting them to extend or rise above the top, where they may be provided with suitable ornamentation. The sides also engage the ends of the top, which is arranged between them in such a manner that the top tends to main-

tain them in substantially parallel relation and substantially at right angles to the sides of the crib, thus lending rigidity to the structure.

While only one embodiment of the invention is shown and described herein, it will be understood that this application is intended to cover such changes or modifications as may come within the spirit or scope of the following claims.

I claim:

1. A folding crib comprising side members, end members pivotally connected thereto and each adapted to move from a position at right angles to and connecting the ends of the side members to a folded position substantially parallel with and between the side members, panels on the side members having their upper edges arranged in a plane beneath the tops of the end members, a substantially rectangular top supported on said panels between the end members and engaging the inner faces thereof to retain them in spaced parallel relation, said top being provided with grooves in its opposite ends, pins projecting inwardly from one of the side members and engaging said grooves whereby the top is movable to a vertical position on said pins as an axis to a position parallel with the sides and in a vertical plane suspended on the pins, or in a substantially horizontal plane on the pins from said position on the panels and to the vertical position parallel with the sides on said pins as an axis and suspended therefrom, and means on the top projecting over the outer walls of the side panels for retaining the top against sliding movement thereon.

2. A folding crib comprising a pair of side members, each of said side members comprising side panels arranged between end posts projecting above the panels, at least one of said panels comprising two parts the lower one of which is fixed to the posts and the upper one hinged to said lower part to swing from a position between the posts outwardly and downwardly to a position arranged in a plane parallel to and adjacent the lower part, end members arranged between said posts and pivoted to one of the side members to swing inwardly to a position adjacent thereto, a substantially rectangular top supported on and projecting over said side panels between the end posts and engaging the inner faces of the end members to retain them in parallel relation, and a bead on said top and projecting downwardly therefrom to engage said hinged part of the side member to retain it in normal closed position.

3. A folding crib comprising a pair of side members each comprising end posts and side panels arranged between the posts, a pair of end members arranged between the posts and pivotally connected thereto, said end

members rising above the plane of the upper edges of the side panels, a top member supported on said side members having grooves in its opposite ends each of said grooves being open at one end and closed at its other end, inwardly projecting pins on the posts of one of said sides arranged to engage said grooves and on which the top is slidably horizontally from the crib and movable to a vertical plane suspended on said pins, brackets on the posts in which the pins are mounted and resiliently engaged thereby, and keepers on the top projecting over the open ends of the grooves and having slots registering with the grooves and arranged to receive the pins when the top is in its normal position on the crib.

In witness whereof, I have hereunto signed my name.

20 HARRY E. McCANDLESS.
